His Attorney

UNITED STATES PATENT OFFICE.

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed May 15, 1928. Serial No. 277,839.

My invention relates to railway signaling, and particularly to signaling for railroad yards such as classification yards and distribution yards.

5 I will describe one form of signalling embodying my invention, and will then point out the novel features thereof in claims.

The accompanying drawing is a diagrammatic view showing one form of signaling 10 embodying my invention.

Referring to the drawing, the reference character 10 designates a main track, and the reference characters 1, 2, 3, and 4 designate auxiliary tracks which are connected 15 with the main track by switches C, D, and E. When switch C is in its normal position, traffic may proceed from the auxiliary track 1 into the main track 10. When switches C and D are both reversed, traffic may proceed 20 from track 2 into main track 10. When switch C is reversed and switches D and E are normal, traffic may proceed from track 3 into track 10. When switches C and E are reversed and switch D is normal, traffic 25 may proceed from track 4 into track 10.

Each track 1, 2, 3, and 4 is provided with a signal designated by the reference character S with an exponent corresponding to the associated track, which signals govern 30 traffic from their respective auxiliary tracks into the main track 10. Each signal comprises a proceed lamp G and a stop lamp R.

The signals S are controlled by a relay F, and by certain controllers 5 and 6 operated 35 by the several switches C, D, and E. Relay F is controlled in any suitable manner, the circuit for this relay being omitted because it has nothing to do with my present invention.

40 I will first assume that relay F is energized and that all three switches C, D, and E are normal. The proceed lamp G of signal S¹ is then lighted, the circuit being from terminal B of a suitable source of current, through contact 7 of relay F, circuit controller 5^C, lamp G of signal S¹, to terminal O of the same source of current. Lamp R of signal S¹ is then extinguished because there is no circuit through this lamp. Lamp R

45 of signal S² is lighted, the circuit being from terminal B through contact 8 of relay F, contact 6^C, asymmetric unit U¹⁰ and lamp R of signal S² to terminal O. Lamp R of signal S³ is lighted by virtue of a circuit 50 which passes from terminal B through con-

tact 8 of relay F, contact 6^C, asymmetric unit U¹² and lamp R of signal S³ to terminal O. Lamp R of signal S⁴ is lighted by virtue of a similar circuit which includes contacts 8 and 6^C and asymmetric unit U¹¹. The lamp G of each signal S², S³, and S⁴ is extinguished because there are no closed circuits through these lamps.

I will now assume that switches C and D have been reversed to permit traffic from track 2 into track 10. Lamp G of signal S² is then lighted, its circuit being from terminal B through contact 7 of relay F, contact 5^C, contact 5^D, and lamp G of signal S² to terminal O. Lamp R of signal S² and the 55 lamps G of signals S¹, S³, and S⁴ are all extinguished because there are no closed circuits through these lamps. Lamp R of signal S¹ is lighted by virtue of a circuit from terminal B through contact 8 of relay F, contact 6^C, and asymmetric unit U¹³. Lamp R of signal S³ is lighted by virtue of a circuit through contact 8, contacts 6^C and 6^D, and asymmetric unit U⁶. Lamp R of signal S⁴ is lighted by virtue of circuit through 60 contact 8, contacts 6^C and 6^D, and asymmetric unit U⁵.

If switch C is reversed and switches D and E are both normal, lamp G of signal S³ is lighted, the circuit being through contact 7 65 of relay F, contact 5^C, contact 5^D, and contact 5^E. The circuit for lamp R of signal S¹ then includes contact 6^C and asymmetric unit U¹³. The circuit for lamp R of signal S² includes contacts 6^C and 6^D and asymmetric unit U⁹. The circuit for lamp R of signal S⁴ includes contacts 6^C, 6^D, 6^E, and asymmetric unit U⁸.

If switches C and E are reversed and switch D is normal, lamp G of signal S⁴ is 70 lighted by a circuit which includes contacts 5^C, 5^D, and 5^E. The circuit for lamp R of signal S¹ then includes contact 6^C and asymmetric unit U¹³. The circuit for lamp R of signal S² includes contacts 6^C and 6^D and asymmetric unit U⁹. The circuit for lamp R of signal S³ includes contacts 6^C, 6^D, and 6^E and asymmetric unit U⁷.

When relay F is de-energized, all the circuits traced or referred to above are open 75 at contacts 7 and 8 of this relay. The stop lamp R of each signal is then lighted by virtue of a circuit which passes from terminal B, through back contact 9 of relay F, and the four stop lamps R connected in multiple. 80

55 110

The branches for the several lamps R include asymmetric units U^1 , U^2 , U^3 , and U^4 respectively.

Again assuming that relay F is energized, and that switch C is normal, lamp G of signal S^1 is lighted and lamp R of this signal is extinguished. If it were not for asymmetric units U^2 , U^3 , and U^4 current could flow, for example, from terminal B through contact 8, contact 6^C , unit U^{12} , and then through wire 11 and asymmetric unit U^1 to lamp R of signal S^1 . This flow of current is prevented, however, by the presence of asymmetric unit U^3 . In a similar manner, the units U^1 , U^2 , and U^4 function to prevent the lighting of the stop lamp for the signal in which the proceed lamp is lighted.

One function of the units U^5 to U^{13} is to prevent current flowing through contact 9 of relay F to any lamp R except by way of the direct path from unit U^1 , U^2 , U^3 , or U^4 to such lamps. Another function of units U^5 to U^{13} inclusive is to prevent lighting of the stop lamp R in the signal whose proceed lamp G is lighted. Assuming for example that switch C is normal, if it were not for asymmetric unit U^8 , current could flow from battery B through contact 8, contact 6^C , unit U^{11} , contact 6^B , contact 6^D , unit U^{13} , and lamp R of signal S^1 to terminal O. Under the different conditions of the switches C, D, and E, the various units U^5 to U^{13} function in manners which will readily be understood to prevent lighting of the stop lamp for the signal in which the proceed lamp is lighted.

The asymmetric units U avoid the necessity for relays associated with the signals to selectively control the signal lamps in accordance with the positions of switches C, D, and E.

Although I have herein shown and described only one form of signaling embodying my invention, it is understood that various changes and modifications may be made therein within the scope of the appended claims without departing from the spirit and scope of my invention.

Having thus described my invention, what I claim is:

1. A railroad yard comprising a main track and a plurality of auxiliary tracks, switches for permitting traffic from any one of said auxiliary tracks into said main track, a signal for each auxiliary track comprising a proceed lamp and a stop lamp, circuit controllers operated by said switches, and means including said circuit controllers for lighting the proceed lamp of any one signal when said switches are set for traffic from the associated auxiliary track into said main track and for lighting the stop lamp of each of the remaining signals.

2. A railroad yard comprising a main track and a plurality of auxiliary tracks,

switches for permitting traffic from any one of said auxiliary tracks into said main track, a signal for each auxiliary track comprising a proceed lamp and a stop lamp, circuit controllers operated by said switches, a relay, means including a front contact of said relay and said switch operated circuit controllers for lighting the proceed lamp of any one of said signals when said switches are set for traffic from the associated track into said main track, and means including a front contact of said relay for lighting the stop lamp of each of the remaining signals.

3. A railroad yard comprising a main track and a plurality of auxiliary tracks, switches for permitting traffic from any one of said auxiliary tracks into said main track, a signal for each auxiliary track comprising a proceed lamp and a stop lamp, circuit controllers operated by said switches, a relay, means including a front contact of said relay and said switch operated circuit controllers for lighting the proceed lamp of any one of said signals when said switches are set for traffic from the associated track into said main track, means including a front contact of said relay for lighting the stop lamp of each of the remaining signals, and means including a back contact of said relay for lighting the stop lamp of each of said signals.

4. A railroad yard comprising a main track and a plurality of auxiliary tracks, switches for permitting traffic from any one of said auxiliary tracks into said main track, a signal for each auxiliary track comprising a proceed lamp and a stop lamp, a relay, means operating when said relay is de-energized to light the stop lamp of each signal, and means operating when said relay is energized and said switches are set for traffic from one of said auxiliary tracks into said main track to light the proceed lamp of the signal for such auxiliary track and the stop lamp of each of the remaining signals.

5. A railroad yard comprising a main track and a plurality of auxiliary tracks, switches for permitting traffic from any one of said auxiliary tracks into said main track, a signal for each auxiliary track comprising a proceed lamp and a stop lamp, circuit controllers operated by said switches, a relay, a circuit including a source of current and a back contact of said relay, said circuit having a plurality of multiple branches including the stop lamps of said several signals respectively, means including a front contact of said relay and governed by said circuit controllers for selectively supplying current to said multiple branches according to the positions of said switches, asymmetric units included in said branches for preventing the supply of current to the stop lamp of one

signal through said front contact, and means including a front contact of said relay and controlled by said circuit controllers for supplying current to the proceed lamp of 5 said one signal.

6. A railroad yard comprising a main track and a plurality of auxiliary tracks, switches for permitting traffic from any one of said auxiliary tracks into said main track, 10 a signal for each auxiliary track comprising a proceed lamp and a stop lamp, circuit controllers operated by said switches, a relay, a circuit including a back contact of said relay for supplying current to all of said 15 stop lamps in multiple regardless of the positions of said switches, a second circuit including a front contact of said relay and controlled by said switch operated circuit controllers for supplying current to the stop 20 lamp of all signals except one, asymmetric units in the first of said circuits for preventing the supply of current to the stop lamp of said one signal when the second circuit is closed, and means including a front contact 25 of said relay and controlled by said circuit controllers for supplying current to the proceed lamp of said one signal.

7. A railroad yard comprising a main track and a plurality of auxiliary tracks, 30 switches for permitting traffic from any one of said auxiliary tracks into said main track, a signal for each auxiliary track comprising a proceed lamp and a stop lamp, a relay, a circuit having a plurality of multiple 35 branches including the stop lamps of said

several signals respectively, means operating when said relay is deenergized to supply current to all of said branches, a second means operating when said relay is energized and said switches are set for traffic 40 from one of said auxiliary tracks into said main track to light the proceed lamp of the signal for such auxiliary track and to supply current to all of said branches except the one for the stop lamp of the signal in which 45 the proceed lamp is lighted, and asymmetric units included in said branches for preventing the supply of current by said second means to the stop lamp of the signal in which the proceed lamp is lighted. 50

8. A railroad yard comprising a main track and a plurality of auxiliary tracks, switches for permitting traffic from any one of said auxiliary tracks into said main track, a signal for each auxiliary track comprising 55 a proceed lamp and a stop lamp, circuit controllers operated by said switches, circuits for said stop lamps including said circuit controllers, means including said circuit controllers for lighting the proceed lamp 60 of any one signal when said switches are set for traffic from the associated auxiliary track to the main track, and asymmetric units associated with said stop lamp circuits for preventing the lighting of the stop lamp 65 for the signal in which the proceed lamp is lighted.

In testimony whereof I affix my signature.

LESTER E. SPRAY.
